Primary Examiner — Amber R Stiles*Assistant Examiner* — Tia Ruth-Renee Polidori(74) *Attorney, Agent, or Firm* — Shen Huang(57) **CLAIM**

The ornamental design for a bottle, as shown and described.

DESCRIPTION

FIG. 1 is a front elevation view of a bottle, showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a front, right side and top perspective view thereof;

FIG. 7 is a rear, right side and top perspective view thereof; and,

FIG. 8 is a left side and top perspective view thereof.

The portions of the bottle shown in broken lines form no part of the claimed design.

1 Claim, 8 Drawing Sheets(56)
